PUMP, ENGINE, AND THE LIKE

Leonard George Savage, South Farnborough,
EnglandApplication February 26, 1937, Serial No. 127,986
In Great Britain February 27, 1936

5 Claims. (Cl. 103—117)

This invention relates to improvements in displacement pumps, engines, and the like for displacing gases or liquids.

One of the particular objects of the present invention is to provide a rotary fluid displacement mechanism employing internal vanes each comprising a shaped surface forming at least the outer half of one side of the vane and an abutting portion on each vane adapted to coact slidingly with substantially the whole of the shaped surface of the next adjacent vane whereby the volume of the fluid chambers successively formed by coacting vanes may be reduced from a maximum to substantially zero.

Another object of my invention is to provide a rotary fluid displacement mechanism wherein the shaped surface of each vane forms substantially an entire side of said vane, each vane having an abutting portion which may be formed by the inner end of said vane, which abutting portion coacts slidingly with substantially the whole of the shaped surface for varying the volume of the fluid chambers between maximum and substantially zero.

As a further object, the invention seeks to provide structure of this character wherein coaction between adjacent vanes will take place whereby the induction and exhaust periods of each fluid compartment may correspond to more than half a revolution of the crank device relative to the casing.

The invention is illustrated by way of example in the accompanying drawings, in which:—

Figure 1 is a diagrammatic sectional elevation showing one form of pump;

Figure 2 is a similar view of a modified construction of pump;

Figure 3 is a section taken on the line 3—3 of Figure 2;

Figure 4 is a sectional elevation of a modified form of pump taken on the line 4—4 of Figure 5; and

Figure 5 is a sectional side elevation on the line 5—5 of Figure 4.

In a casing 1 the outer portion 2 of a vane is free to oscillate about a fixed fulcrum. The inner portion 4 of the vane is articulated at 5 to the outer portion 2 of the vane. The vane portion 4 is connected by a bearing 6 to a crankpin 8 of a crank 9. As the roots of all the vane parts 4 are attached to the crankpin at a common point, they may be hinged or articulated in such a manner that all the vanes are co-planar and make contact with both ends of the casing.

Ports or valves 10 are provided for each com-

partment formed between adjacent vanes at the periphery of the casing 1, and similar ports or valves 11 are provided in the end covers or in other suitable position so disposed that they may be covered or uncovered by the vanes 2 and 4 during motion. Depending on the direction of rotation of the crank with respect to the casing, the ports or valves 10 and 11 may form either the inlet or outlet ports or valves.

In the operation of the arrangement illustrated in Figure 1, rotation of the crankpin 8 in a clockwise direction from the position shown causes the outer portion of the vanes 2 successively to cover the ports or valves 11 and compress the fluid between adjacent pairs of the inner portion 15 of the vanes 4 until it has been compressed and transferred to the space bounded by adjacent pairs of the outer portions of the vanes 2. At this point also the articulation 12 of the left hand outer vanes associates with the shaped surfaces 13 of the right hand outer vanes (speaking relative to one compartment) making a fluid seal therewith. Continued motion of the crank in a clockwise direction compresses the fluid and delivers it through the valve 10 at the periphery 25 of the casing. In the meanwhile, the space bounded by adjacent pairs of the inner vanes is increasing and continued movement uncovers the ports 11 so that fresh fluid is induced into the inner compartment. Continued rotation then causes the articulation 12 of the outer vanes to recede from the sealing surface of the right hand outer vanes whereby the outer and inner portions of the space become one and the induction stroke continues until the port 11 is 35 again covered and the sequence of operations repeated.

Each compartment formed by successive pairs of vanes operates in like manner and in succession. The progressive delivery so obtained may 40 be collected in an annular chamber, duct or pipe 14 and delivered at a common outlet, if desired, or each individual delivery may be utilized as required.

Rotation of the crank in an anti-clockwise 45 direction may be adopted. In this case the sequence of operations is reversed in the sense that the valves at the periphery of the casing become the inlet valves, and the valves or ports uncovered by the vanes become the outlet valves. In 50 this case the initial compression takes place between adjacent pairs of outer vanes and the casing wall and the final compression between adjacent pairs of the inner vanes.

To improve the balance, the casing may be 55

subdivided transversely by division plates and the successive units coupled in such a manner that the crankpin masses tend to balance one another.

In an alternative form of the invention, the 5 crank 9 may be fixed, and the casing 1 may be free to rotate about the axis of the crank, within a stationary outer casing. In this form a fewer number of ports or valves may be used as the progressive nature of the delivery from 10 successive compartments enables the discharge to take place through one or more fixed ports in the stationary outer casing during a limited angle of rotation.

According to a further feature of the invention, 15 a sleeve fixed to the crank or geared thereto may be provided for controlling inlet or outlet ports in the peripheral wall of the casing.

The sleeve may be rotatable relative to the outer casing to permit timing of the period of 20 inlet and outlet and variation of the degree of compression.

In Figures 2 and 3, a casing 15 is rotatably mounted about the axis of a crank 16, and the outer portions 17 of articulated vanes are evenly 25 spaced apart at the tips in the casing by pivot axes 18 fixed in the casing. The inner portions 19 of the vanes are articulated at 20 to the outer portion of the vanes and at the root ends are connected to a common crankpin 21 of the fixed 30 crank 16. The crank web 22 of the fixed crank 16 forms a disc through which inlet ports 23 are cut.

Enclosing the rotary casing 15 is a fixed casing 24 provided with inlet or outlet ports 25, and 35 interposed between the casing 15 and 24 is a sleeve 26 mounted within the outer casing so as to be rotatable relative thereto through a limited angle. This sleeve 26 is provided with a port 27 so arranged that it can register with 40 and vary the length of the port 25 of the outer casing 24. The sleeve may be rotated by means of a lever 28 or by other means.

In the operation of the arrangement illustrated, 45 rotation of the casing 15 in an anti-clockwise direction from the position shown causes the vanes successively to induce and compress the fluid in the manner already described, and the delivery from each compartment takes place as ports 29 in the casing 15 in turn register with the ports 27 of the sleeve and the ports 50 25 of the outer casing.

Operation of the sleeve 26 in an anti-clockwise direction from the position shown causes the ports 29 in the rotary casing to open later in 55 relation to the stroke of the vanes so that the internal pressure is raised to a higher degree before delivery takes place.

The further construction shown in Figures 4 and 5 resembles that of Figure 1 in so far as 60 the casing 1 is stationary and that each of the working spaces indicated at 30 is provided with a non-return valve 10 leading into a common delivery chamber 14. The vanes which in this case are shown at 31 are in one piece and are secured at their outer ends to spindles 32 which 65 pass through the end wall 33 of the casing 1. They are there provided each with an arm 34 having at its inner end a pin and roller 35 which engages a cam groove 36 and acts as a follower. The cam groove 36 is circular but is eccentrically formed in the face of a disc 37 which is driven by a shaft 38 thereby causing the vanes 31 to execute an oscillatory movement, the various stages of which will be seen in Figure 4. 70 The inlet 39 to the pump is disposed at the centre 75

and feeds the casing 1 with the liquid or other fluid to be pumped. As each vane commences to move outwardly it coacts with the next succeeding vane and entraps some fluid which is thus forced outwardly through the corresponding delivery valve 10 as the vane assumes the outermost position in which it lies in circumferential engagement with the casing 1. The outer casing or body 40 is provided with a common delivery passage 41.

It will be understood that although the examples have been described with particular reference to pumps, the invention is applicable to fluid driven motors, as it is only necessary to feed the delivery passages with liquid or other fluid under pressure and arrange for the valves to be mechanically actuated. The improved fluid-displacing mechanism may further be utilized as an engine.

What I claim is:

1. A rotary fluid displacement mechanism comprising a substantially cylindrical casing, inlet and outlet fluid passages in the casing, a crank device adjacent one end of the casing, a plurality of inwardly directed vanes pivoted equidistantly 25 around the periphery of the interior of the casing and connected to the crank device, a shaped surface forming at least the outer half of one side of each vane, and an abutting portion on each vane adapted to coact slidably with substantially the 30 whole of the shaped surface of the next adjacent vane, the volume of the fluid chambers successively formed by coacting vanes and the casing being thereby reduced from a maximum to substantially zero.

2. A rotary fluid displacement mechanism comprising a substantially cylindrical casing, inlet and outlet fluid passages in the casing, a crank device adjacent one end thereof, a plurality of inwardly directed vanes pivoted equidistantly 40 around the periphery of the interior of the casing and connected to the crank device, a shaped surface forming substantially the whole of one side of each vane and an abutting portion on each vane adapted to coact slidably with substantially the 45 whole of the shaped surface of the next adjacent vane, the volume of the fluid chambers successively formed by coacting vanes and the casing being thereby reduced from a maximum to substantially zero.

3. A rotary fluid displacement mechanism comprising a substantially cylindrical casing, inlet and outlet fluid passages in the casing, a crank device adjacent one end thereof, a plurality of inwardly directed vanes pivoted equidistantly 55 around the periphery of the interior of the casing and connected to the crank device, a shaped surface forming substantially the whole of one side of each vane and an abutting portion constituted by the inner end of each vane which is adapted to coact slidably with substantially the 60 whole of the shaped surface of the next adjacent vane, to reduce the volume of each of the fluid chambers successively formed by coacting vanes and the casing from a maximum to substantially zero.

4. A rotary fluid displacement mechanism comprising a substantially cylindrical casing, inlet and outlet fluid passages in the casing, a crank device adjacent one end thereof, a plurality of transverse spindles mounted equidistantly in the end walls of the casing and adapted to be rocked by means of said crank device, a plurality of inwardly directed vanes each carried by one of said spindles, a shaped surface forming substantially 70 75

the whole of one side of each vane and an abutting portion on each vane adapted to coact slidely with substantially the whole of the shaped surface of the next adjacent vane, the volume of the fluid chambers successively formed by coacting vanes and the casing being thereby reduced from a maximum to substantially zero.

5. A rotary fluid displacement mechanism comprising a substantially cylindrical casing, inlet and outlet fluid passages in the casing, a crank device adjacent one end of the casing, a plurality of inwardly directed articulated vanes pivoted equidistantly around the periphery of the interior

of the casing and connected to the crank device, a shaped surface forming substantially the whole of one side of the outer member of each vane, and an abutting portion adjacent the joint portion of the vane members, the abutting portion 5 of each vane being adapted to coact slidely with substantially the whole of the shaped surface of the outer member of the next adjacent vane so as to vary the volume of each fluid chamber, one complete cycle of variation corresponding to 10 more than one revolution of the crank device.

LEONARD GEORGE SAVAGE.
